UNITED STATES PATENT OFFICE

149,501

DESIGN FOR A MUSICAL CIGARETTE BOX OR SIMILAR ARTICLE

Eli Jaye, New York, N. Y.

Application February 11, 1946, Serial No. 126,446

Term of patent 3½ years

(Cl. D85—2)

To all whom it may concern:

It is known that I, Eli Jaye, a citizen of the United States, residing at New York, in the county of Bronx and State of New York, have invented a new, original, and ornamental Design for a Musical Cigarette Box or Similar Article, of which the following is a specification, reference being had to the accompanying drawings, forming part thereof.

Figure 1 is a perspective view, with the cover open, of my design for a musical cigarette box or similar article.

I claim:

The ornamental design for a musical cigarette box or similar article, as shown.

ELI JAYE.
